UNITED STATES PATENT OFFICE.

MICHAEL PARIDON, OF BARBERTON, OHIO, ASSIGNOR OF ONE-HALF TO HENRY A. RUDD, OF BARBERTON, OHIO.

MACHINE FOR MAKING PNEUMATIC-TIRE SHOES.

1,200,016.

Specification of Letters Patent.

Patented Oct. 3, 1916.

Application filed June 19, 1916. Serial No. 104,562.

To all whom it may concern:

Be it known that I, MICHAEL PARIDON, a citizen of the United States, residing at Barberton, in the county of Summit and State of Ohio, have invented new and useful Improvements in Machines for Making Pneumatic-Tire Shoes, of which the following is a specification.

This invention relates to machines for forming a strength-giving fabric adapted for incorporation in a pneumatic-tire-shoe, from a flexible member, such for instance, as a cord, wound helically about a pair of separated bead cores, so supported as to revolve in parallel planes about a common axis of revolution during the winding operation.

The object of the invention is to provide a machine having means to support a pair of ring-like bead cores in parallelism during their revolution about a common axis of revolution, the supports for said bead cores provided with means interengaging therewith to secure a positive movement or revolution of the bead cores in unison with the supporting means and with each other.

A further object is to provide a shuttle revolute in a plane intersecting the planes of revolution of said cores and provided with a bobbin-carrier equipped with a bobbin carrying a winding of cord for helical, simultaneous application about the two spaced revolving cores. The mechanism for revolving the shuttle has direct connection with the core supporting means to insure the simultaneous and synchronous movement of the cores and shuttle in the winding of the cord about the cores, to the end that upon a determinate number of complete revolutions of the cores the fabric will be fully and completely fashioned. In order to insure the accurate placement of the cord during the winding operation the cores are provided with helically-disposed grooves in their outer faces which constitute seats for the reception of the looped portions of the cord wound about them and they also provide means for interengaging or intermeshing of the cores with the supporting means whereby the revolution of the cores in unison with their supporting means and with each other is positively insured.

With the foregoing and other objects in

view, the invention consists in the novel construction, combination and arrangement of parts constituting the invention to be hereinafter specifically described and illustrated in the accompanying drawings which form a part hereof wherein is shown the preferred embodiment of the invention, but it is to be understood that changes, variations and modifications can be resorted to which come within the scope of the matter hereinafter claimed.

In the drawings in which similar reference numerals indicate like parts in the different figures, Figure 1, is a view in side elevation of a machine embodying the present invention. Fig. 2, is a front elevation of the machine shown in Fig. 1 and looking from the left in Fig. 1. Fig. 3, is a horizontal, sectional view taken on line 3—3 of the shuttle support, and Fig. 4, is a view of a pair of spaced bead cores adapted for use in connection with the machine shown in Figs. 1 and 2 and with a winding of cord thereon, the figure being somewhat diagrammatic.

Referring to the drawings in detail reference numeral 1 denotes a supporting base 1 on which are mounted a pair of upright standards 2 and 3. The standard 2 is provided with a bearing (not shown) for a horizontal shaft 5 and above which is a bearing (not shown) for a rotatable shaft 7. The shafts 5 and 7 are preferably in vertical alinement with each other. The standard 3 is provided with a bearing 8 for a horizontal, rotatable shaft 9 above which is a bearing 10 for a rotatable shaft 11. The shafts 9 and 11 are in vertical alinement and the arrangement of the shafts is such that the shafts 5 and 9 are in horizontal alinement and the shafts 7 and 11 are also similarly disposed. The standard 3 is provided with a laterally offset bracket 12 in which is a bearing 13 for a shaft 14, in parallelism with the shafts 5, 7, 9 and 11. The shafts 5, 7, 9, 11 and 14 bear sprocket-wheels numbered respectively 15, 16, 17, 18 and 19. Extending around and engaging with the sprocket-wheels 15—19 inclusive is a sprocket chain 20, so that all of the sprocket-wheels revolve in unison and at approximately the same speed of revolution. Mounted on the base 1 is a bracket 21 the upper portion of which is provided with a

bearing 22 for a counter-shaft 23 which bears a sprocket-wheel 24. Also mounted on the shaft 14 is a sprocket-wheel 25 and extending between and around the sprocket-wheels 24 and 25 is a sprocket chain 26 for communicating motion from one shaft to the other. Mounted on the front end of the shaft 23 is a worm-wheel 27.

Mounted on the base 1 is a bracket 28 the upper end of which is provided with a journal bearing 29 for a shaft 30 one end of which is provided with a worm 31 intermeshing with the worm-wheel 27. The front end of the shaft 30 is provided with a pinion-gear 32 and also with a large spur-gear 33. Mounted on the base 1 is a motor gear 33. Mounted on the base 1 is a motor gear 33, on the armature shaft of which is a pinion-gear 35 adapted to intermesh with the gear 33 for rotating the shaft 30 and the previously described mechanism.

Splined respectively on the shafts 5, 7, 9 and 11 are sleeves 40, 41, 42 and 43 respectively and as these sleeves are all similar a description of one is believed to be sufficient for the understanding of them all and attention is therefore directed to Fig. 1. Each sleeve embodies a main body portion 44 provided at the ends with grooved roller-like enlargements 45 and 46 similar to each other and provided with peripheral teeth 47, spirally-disposed for a purpose to be later described. It may be pointed out that all of the grooved enlargements 45 on the various shafts 5, 7, 9 and 11 are in transverse alignment with each other and all the grooved enlargements 46 are in alignment with each other. The inner or rear portions of the various sleeves, 40-43 inclusive, are provided with peripheral grooves 48, and secured to the bearings for each of the shafts 5, 7, 9 and 11 are snap-catches or locks 49 adapted to engage in the grooves 48 for holding the various sleeves 40-43 inclusive from longitudinal movement on their respective shafts.

The various grooved enlargements 45 are adapted to constitute rotatable seats or supports for a ring-like or annularly-formed bead core 50 and the grooved enlargements 46 on the various sleeves 40-43 inclusive are adapted to form similar seats for a ring-like or annularly fashioned bead-core 51. The bead-cores 50 and 51 are similarly fashioned and hence a description of one is believed to be sufficient for the understanding of both. These bead-cores are shown best in Fig. 4 and usually comprise a pair of annularly-fashioned or ring-like members 52 the outer face of each of which is provided with a helically or spirally disposed groove 53 alternating with a similarly formed rib 54, the groove 53 constituting seats and a spacing medium for a cord 55 which is to be wound thereabout as shown in Fig. 4. It is contemplated that the cord

is continuous and that the speed of rotation of the two beads will be uniform and sufficient to insure the placement of the core about the two bead cores in such a manner that the cords extending in one direction from one bead core to the other will be at right angles to the other portion of the same cord extending from the second core to the first core. The grooves 53 and the spiral ribs 54 are preferably in the general form of an ordinary V-thread, the pitch, inclination, general cross-sectional configuration, etc., being immaterial to this invention but these grooves and ribs will correspond in contour and pitch to the grooves and corresponding ribs 47 on the grooved portions of the enlargements 45 and 46 of the various sleeves 40-43 inclusive. When the two bead cores 50 and 51 are mounted so that the teeth or threads thereon are adapted to intermesh with the corresponding portions of the enlargements 45 and 46 on the sleeves 40-43 inclusive and the latter are rotated through the mechanism previously described the two bead cores will revolve in parallel planes at similar speeds and no danger of one bead core traveling faster than the other can occur. Furthermore, the enlargements 45 and 46 on the various sleeves 40-43 inclusive constitute spacing instrumentalities for positively holding the two bead cores 50 and 51 at determinate distances apart.

Mounted on the base 1 is a housing 60 provided with bearings 61 for the shaft 30 and having in the upper portion an approximately arcuate channel 62 provided with an offset portion 63 forming cylindrical bearing for a purpose to be later described. Co-operating with the housing 60 is a cover 64 secured to the housing 60 by holding means 65 and also provided with an offset portion 66 horizontally parallel with the offset portion 63 so that the two form a cylindrical bearing for a shuttle to be later described.

Mounted in the cylindrical bearing in the housing 60 and cover 64, is a shuttle 67 in the form of a broken annulus having rabbeted side portions to seat on the two bearings 63 and 66 and with a projecting intermediate portion provided with spur-teeth 68 adapted to intermesh with a pair of spur-gears 69 and 70 mounted on transverse shafts 71 and 72 in the housing 60 and which intermesh with the pinion 32. Secured to the inner face of the shuttle 67 is a bobbin-carrier 80 provided with a shaft 81 on which is a bobbin 82 to receive the cord 55. Also mounted on the bobbin-carrier is a tension device of any preferred description and shown in the drawings as consisting of a pair of pins or shafts 83 around which the cord 55 passes in its passage from the bobbin 82 to the two bead cores 50 and 51.

The operation of the device is as follows:

Motion communicated to the pinion 35 by the motor 34, is communicated through the spur-gear 33 to the shaft 30 and this motion is slowly transmitted through the worm 31 to the worm-wheel 27, the shaft 33, the sprocket-wheel 24, the sprocket-chain 26, sprocket-wheel 25, to the shaft 14. The sprocket-chain 20 transmits this motion simultaneously and evenly to the shafts 5, 7, 9 and 11 thereby revolving the various sleeves 40-43 inclusive, causing the simultaneous, even and uniform revolution of the two bead forming cores 50 and 51. During the revolution of these two bead cores in unison the shuttle 67 is rotated by the motion transmitted from the shaft 30 and gear 32 to the two gears 69 and 70 and from them to the teeth 68 on the shuttle 67 due to the intermeshing of the teeth in the gears 69 and 70 with the teeth 68 on the shuttle so that the two bead cores 50 and 51 are revolved in parallel planes which are intersected by the plane of revolution of the shuttle carrying the bobbin 82. As the shuttle revolves the cord 55 is unwound from the bobbin and wound around the two bead cores in the manner diagrammatically shown in Fig. 4 and the revolutions of the various portions of the mechanism will be so timed that each convolution of the cord about the two beads will be such that each looped portion of the cord will be seated in one of the convolutions of one of the grooves 53 in the bead cores and this is kept up until a complete fabric is furnished after which the spring catches 49 are released and the various sleeves 40-43 inclusive are slid to the left, Fig. 1, on their respective shafts sufficiently to clear the sleeves 40 and 42 from their supporting shafts, after which the tire-shoe fabric can be passed outwardly through the opening in the broken shuttle and fresh bead cores placed in position and the parts returned to their normal operative position. It is preferred that two shafts 7 and 11 be made longer than the shafts 5 and 9 as shown in Fig. 1 so that it is not necessary to remove the sleeves 41 and 43 from these respective shafts in order to free the completed tire-shoe fabric from them.

I claim,

1. A machine of the class described comprising rotatable supporting members for revolving a pair of ring-like bead cores in parallel planes, said members provided with means interengaging with said bead cores to insure positive revolution of the latter, a shuttle revolving in a plane intersecting the planes of revolution of said cores, a bobbin provided with a winding of tire-shoe building material mounted on said shuttle for wrapping said material helically about said cores, and means to simultaneously revolve said cores and shuttle.

2. A machine of the class described com-

prising rotatable members constituting supports for a pair of ring-like bead cores revoluble in parallel planes, said members provided with means interengaging with said bead cores to insure positive revolution of the latter, a shuttle in the form of a broken annulus revolving in a plane intersecting the planes of revolution of said cores, a bobbin provided with a winding of tire-shoe building material mounted on said shuttle for orbital movement about said cores and arranged to wrap said material helically about said cores, and means to simultaneously revolve said cores and shuttle.

3. A machine of the class described comprising suitably mounted grooved rollers, means for rotating all of said rollers in unison, said rollers constituting supporting means for holding a pair of ring-like bead cores during their revolution in parallel planes, said rollers provided in their grooved portions with means interengaging with corresponding means on said bead cores to insure positive revolution of the latter, a shuttle revoluble in a plane intersecting the planes of revolution of said bead cores, a bobbin provided with a winding of tire-shoe building material mounted on said shuttle for orbital movement about said cores and adapted to wrap said material helically about said cores, and means to simultaneously revolve said cores and shuttle.

4. A machine of the class described comprising a plurality of rotatable shafts, means for revolving said shafts in unison, a grooved roller on each of said shafts and revoluble in unison therewith, the grooves in said rollers provided with intermeshing means, and arranged to constitute seats for supporting and revolving a pair of ring-like bead cores in parallel planes, said bead cores provided with means intermeshing with the grooved portions of said rollers to thereby insure positive revolution of the cores, and a shuttle carrying a winding of tire-shoe building material adapted to move orbitally about said cores for wrapping said material helically thereabout, and means to simultaneously revolve said cores and bobbin.

5. A machine of the class described comprising a plurality of rotatable shafts, means to rotate said shafts in unison, a grooved roller mounted on each shaft, means connecting said shafts and rollers to induce revolution of both in unison, the grooves in said rollers provided with interengaging means, said rollers constituting means for supporting and holding for simultaneous revolution in parallel planes a pair of ring-like bead cores equipped with means to interengage with the grooved portions of said rollers, a bobbin mounted for orbital movement about said cores and equipped with a winding of tire-shoe building material arranged to be placed on said cores in spiral fashion during

1
the movement of said bobbin and means to simultaneously revolve said cores and shuttle.

6. A machine of the class described comprising a plurality of supporting shafts, a grooved roller mounted on each shaft and rotatable in unison therewith, means for simultaneously revolving said shafts, said grooved rollers providing a supporting medium for a pair of ring-like bead cores revoluble in unison and in parallel planes, said bead cores provided with spiral grooves on their outer surface, coöperating interengaging ribs in the grooved portions of said rolling 10 ribs to thereby insure positive revolution of the cores, a shuttle revoluble in a plane intersecting the planes of revolution of said cores, a bobbin-carrier on said shuttle, a bobbin on said carrier equipped with a winding of tire-shoe winding material and movable orbitally about said cores for wrapping said material helically thereon, and means connecting said supporting members and said shuttle for insuring simultaneous 20 and said shuttle for insuring simultaneous 25 operation thereon.

7. A machine of the class described comprising a supporting frame, a plurality of

rotatable shafts supported thereby, a pair of grooved rollers mounted on each shaft and rotatable in unison with each other and 30 with their respective shafts, means to simultaneously rotate all of said shafts in the same direction, corresponding members of each pair of rollers arranged in alinement with the corresponding members of the 35 other pairs of rollers and in planes transverse to the axes of said shafts, the grooved portions of said rollers provided with inter-engaging means and constituting supports for a pair of ring-like bead cores revoluble 40 in parallel planes and in spaced relation and furthermore equipped with means on their outer surfaces for interengagement with the grooved portions of said rollers, and a shuttle revoluble in a plane intersecting the planes of revolution of said cores, a bobbin provided with a winding of tire-shoe 45 building material mounted on said shuttle for wrapping said material helically about said cores and means to simultaneously revolve 50 said cores and shuttle.

In testimony whereof I have hereunto set my hand.

MICHAEL PARIDON.
